(57) **CLAIM**

We claim the ornamental design for a volatile substances evaporator, as shown and described.

DESCRIPTION

FIG. 1 is a front perspective view of one embodiment of a volatile substances evaporator showing our new design;

FIG. 2 is a front elevation thereof;

FIG. 3 is a right side elevation thereof;

FIG. 4 is a bottom view thereof;

FIG. 5 is a rear elevation thereof;

FIG. 6 is a left side elevation thereof; and,

FIG. 7 is a top view thereof.
